(57) **CLAIM**

The ornamental design for the transponder holder, as shown and described.

DESCRIPTION

FIG. 1 is a front view of a transponder holder with its suction cups not installed showing my new design;

FIG. 2 is a front view thereof with its suction cups;

FIG. 3 is a rear view of my new design with its suction cups not installed;

FIG. 4 is a rear view thereof with its suction cups;

FIG. 5 is a top view thereof;

FIG. 6 is a bottom view thereof;

FIG. 7 is a right view thereof;

FIG. 8 is a left view thereof;

FIG. 9 is a front perspective view thereof with its suction cups not installed;

FIG. 10 is a front perspective view thereof with its suction cups;

FIG. 11 is a rear perspective view thereof with its suction cups not installed;

FIG. 12 is a rear perspective view thereof with its suction cups;

FIG. 13 is a front perspective view of my new design secured onto a windshield for a transponder to be attached; and,

FIG. 14 is a front perspective view of my new design secured onto a windshield with the transponder mounted thereon.

The broken lines are for environmental purposes only and form no part of the claimed design.
